UNITED STATES PATENT OFFICE

2,360,704

CALCULATING MACHINE

John L. Moody, Oakland, Calif., assignor to Friden Calculating Machine Co., Inc., a corporation of California

Application August 28, 1942, Serial No. 456,492

5 Claims. (Cl. 235—144)

This invention relates to calculating machines and is concerned more particularly with a provision of means for entering a selected pre-set value into the accumulator when such a value is used in repeated calculations.

In certain types of calculating operations, where a series of calculations are to be performed, a value to be entered into the accumulator will be used repeatedly. It is desirable for such series of calculations to pre-set the desired value so that it can be set into the accumulator as a part of a single operation. Such a value for example is often in the form of a constant dividend which is used in a series of dividing operations but with a different divisor in each successive operation.

It is a general object of the invention to provide an improved mechanism for entering a selected value into the accumulator of a calculating machine.

Another object of the invention is to provide a mechanism of the above character where the value entering operation can be performed as an incident to the erasure of a previous figure standing in the accumulator.

Another object of the invention is to provide a mechanism of the above character wherein the values can be entered by means of a single operation.

Another object of the invention is to provide a mechanism which can be manufactured and installed conveniently in the conventional form of calculating machines.

Other objects and advantages of the invention will be apparent from the following description of a preferred embodiment thereof, as illustrated in the accompanying drawings, in which:

Figure 1 is a fragmentary plan view of a calculating machine embodying the instant invention.

Figure 2 is a fragmentary sectional view of a calculating machine taken as indicated by the line 2—2 in Figure 1.

Figure 3 is a fragmentary elevational view partially in section of an adjacent pair of the numeral wheels or dials of the accumulator taken as indicated by the line 3—3 in Figure 2.

Figure 4 is a fragmentary bottom plan view of the carriage of the calculating machine, with some of the parts shown in section.

Figure 5 is a fragmentary plan view of the register carriage with certain parts shown in section. The right hand dial is shown as indicated in the plane of the line 5—5 in Figure 2, the middle dial is shown in the plane indicated by the line 5a—5a in Figure 2, and the left-hand dial is

shown as indicated by the line 5b—5b in Figure 2.

Figure 6 is a view taken similarly to Figure 5, but showing the parts in the position occupied thereby during resetting operations.

Figure 7 is a view similar to Figures 5 and 6, but showing the parts in the position, where they are conditioned for setting of the values into the dials.

10 The instant invention is shown as embodied in a calculating machine of the type disclosed in the patent to Carl M. Friden, No. 2,229,889, issued January 28, 1941, as modified in the co-pending application of Carl M. Friden, Ser. No. 240,269, filed November 14, 1938.

Referring to Figure 1, the calculating machine includes a body portion 10, on which a shiftable register carriage 11 is mounted for ordinal shifting movement in the usual manner. The register carriage supports an accumulator including numeral wheels or dials 12, having manual setting knobs or twirlers 13, and a revolutions counter 14. For entering values into the accumulator, the body of the machine is provided with numeral

25 keys 16 of the usual character which control a conventional form of selecting and actuating mechanism so that values can be entered in the accumulator by depression of plus key 17 or minus key 18. The ordinal position of the entry

30 is controlled by respective shift keys 19 and 20, which cause shifting of carriage 11. Clear key 21 is provided for numeral keys 16, while add key 22 controls clearing of the keyboard after a registration if depressed. The machine also includes

35 a tabulating control key 23, by means of which the carriage can be positioned as selected by setting one of the tabulator keys 24 on the carriage. A division control lever 26 is provided for controlling a conventional form of division mechanism.

40 Power re-setting or clearance operation of the accumulator and the revolutions counter can be performed by depressing return clear key 27 as disclosed in said application 240,269. Manual clearance of the accumulator can be effected by

45 operating handle 28 which controls mechanism later described, while the revolutions counter may be cleared by operating handle 29.

Referring to Figure 2, the accumulator mechanism including the dials 12, mounted on a dial shaft 31, carrying at the lower end a ten-tooth gear 32 which can be selectively engaged with either of ten-tooth gears 33 or 34 at the end of a spool 36 which is slidably and non-rotatably mounted on the square shaft 37. The position of gears 33 and 34 are controlled by positioning of

a gate or bail 38 in a conventional manner under control of the plus and minus keys 17 or 18.

A conventional tens transfer mechanism is provided, including a transfer gear 41, (Figure 2) slidably and non-rotatably mounted on square shaft 31 for movement into the path of a transfer actuator 42 as disclosed in said patent. The transfer gear 41 is provided with a flanged collar 43 for engagement by a down-turned ear 44 of a transfer lever 45 (Figures 2 and 4) which is pivoted on an endwise slideable pivot 46 as later described. Each lever 45 is operated by single-tooth gear 47 on the associated dial shaft 31.

In order to perform the dividend entry as a part of the resetting operation the numeral wheel or dial assemblies are of special construction and have associated therewith, a resetting mechanism for restoring all of the dials to zero and a second resetting mechanism for restoring the dials to a selected value other than zero.

Referring to Figures 2 and 3, each dial shaft 31 is provided with a mutilated gear 51 which is fixed thereon, alternate gears 51 being offset vertically for cooperation with respective vertically offset sets of teeth 52 of a resetting rack 53, mounted for endwise sliding movement in the carriage frame and having an operating handle 54. As seen in Figure 5, rack 53 has a cut-away portion 56 which is opposite the gear 51 when rack 53 is in normal inactive position so that gear 51 can turn freely when the dial is actuated. However, endwise movement of rack 53 past the gears 51 will turn the gears 51 and the associated dials 12 until the mutilated portion of each gear is opposite the rack. During continued movement of the rack, each gear 51 moves into engagement with the associated raised portion 57 of the rack so that the gear 51, shaft 31 and dial 12 are locked against overthrow. The rack 53 is spring-urged in the usual fashion to return to the position shown in Figure 5 after operation by the handle 54.

Each numeral wheel shaft 31 (Figures 2 and 3) also carries a sleeve 61 which at its upper end has a serrated flange 62 engaging a complementary serrated portion 63 secured to the dial 12. At its lower end, each sleeve 61 carries a mutilated gear 64 similar to the gear 51, serrated portions 62 and 63 being spring-urged together by spring 66, compressed between gears 51 and 64. Normally each sleeve 61 and its associated gear 64 turn with the associated dial 12 and its dial shaft 31. Gears 64 of the dials are offset vertically to cooperate with a second resetting rack 67 similar to rack 53. Rack 67 carries operating handle 28. To provide a stop in the selected position of the dials 12 to which they are restored by operation of rack 67, a stop slide 71 (Figure 5) is mounted on the upper surface of the carriage for operation by bellcrank 72 pivoted on pin 73. Bellcrank 72 has a cam edge 74 for engagement by the handle 28 so that the bellcrank 72 is rocked clockwise as viewed in Figure 5 upon operation of handle 28. The movement of slide 71 by operation of rack 67 moves its fingers 76 into the path of the associated teeth 77, carried by respective sleeves 61.

From the above description it will be seen that if the sleeves 61 are locked against movement by adjustment of rack 67 to the position shown in Figure 7, the dials 12 can be turned or set by means of their twirler knobs 13 with respect to the associated sleeve 61 and the stop fingers 76 and resetting gears 64 carried thereby. In this way each dial 12 can be adjusted dif-

ferentially with respect to its normal "zero" position so that it will be restored to a selected value other than "zero" upon subsequent resetting operation of rack 67.

5 During power operation of rack 67 under control of key 27 and endwise movable operating slide 30 as disclosed in said application 240,269, it is desirable to prevent entry of erroneous transfers, and means are provided for disabling 10 the transfer levers 45 with respect to the associated single tooth gears 47 during operation of resetting rack 67. It will be recalled that bellcrank 72 (Fig. 5) and its supporting rod 73 are oscillated clockwise upon operation of handle 28 and resetting rack 67. At its lower end, rod 73 (Figs. 2, 3 and 5) has a finger 81 disposed between upright ears 82 of a slide 83 suitably mounted for endwise sliding movement on the carriage frame and normally positioned as seen 15 in Figures 3 and 5. Slide 83 is formed to provide offset portions 84 (Figure 3) and adjacent cam portions 86. Offset portions 84 are disposed over pivot pins 46 of transfer levers 45. Upon movement of slide 83 to the left by finger 81 during a resetting operation of rack 67, cam portions 86 depress pins 46 so that the transfer levers 45 are moved out of the plane of the associated tripping gears 47. This movement is insufficient to displace spring-urged retaining balls 87 from V-notches 88 in pins 46 so that transfer levers 45 snap back to active position at the end of the operation.

In operation when it is desired to enter a pre-selected figure into the dials of the accumulator 35 the handle 28 is first operated as shown in Figure 7 so that the rack 67 is in locking relation with respect to the mutilated gears 64 associated therewith. Each dial can then be set through the use of its twirler 13 to a desired value, for example the third dial from the right in Figure 7 has been set to the figure "five." During this setting a relative slipping or displacement is effected between the opposed sets of serrations 62 and 63. After this setting is effected and the 40 rack 67 is released, a subsequent resetting operation of the rack 67 by the handle 28 will turn all dials which have been adjusted to the selected values.

Subsequently when it is desired to erase the 50 constant value both of resetting racks 53 and 67 are operated by their respective handles 54 and 28 to the positions shown in Figure 6. In this operation the dial shafts 31 and the dials 12 are restored to "zero" by rack 53 operated on mutilated gears 51 and the sleeves 61 are restored to "zero" relation with respect to the dials by the operation of rack 67 on gear 64.

I claim:

1. In a calculating machine, a register comprising a series of dials, each dial having a shaft, a mutilated resetting gear journalled about the shaft of the associated dial and releasably engaged with said dial to impart driving movement thereto, a resetting rack for said resetting gears for restoring said gears to predetermined positions, differential adjustment of said dials with respect to said gears serving to cause setting of said dials to pre-selected values other than zero in accordance with the differential setting thereof.

2. In a calculating machine, a register comprising a series of dials, each dial having a shaft, a mutilated resetting gear journalled about the shaft of the associated dial and releasably engaged with said dial to impart driving movement

thereto, and a resetting rack for said resetting gears for restoring said gears to predetermined positions, differential adjustment of said dials with respect to said gears serving to cause setting of said dials to pre-selected values other than zero in accordance with the differential setting thereof, another mutilated gear fixed on each of said dial shafts, and a resetting rack associated with said other set of mutilated gears for restoring said gears and said dials to zero registration, whereby simultaneous operation of said resetting rack serves to position said differentially settable elements in zero relation with respect to said dials.

3. In a calculating machine, a register comprising a series of dials, a resetting means, and differentially adjustable connections between said dials and said resetting means, whereby operation of said resetting means sets said dials to selected values in accordance with the adjustments of said connections, and selectively operable means cooperating with said resetting means for adjusting said connections to restore said dials to zero.

4. In a calculating machine, a register comprising a series of dials, a resetting means, and differ-

entially adjustable connections between said dials and said resetting means, whereby operation of said resetting means sets said dials to selected values in accordance with the adjustments of said connections, transfer means operable by said dials, and means controlled by said resetting means upon operation thereof for rendering said transfer means ineffective.

5. In a calculating machine, a register comprising a series of numeral dials secured on vertical shafts, each shaft having a mutilated gear secured thereto, a horizontal resetting rack means slidable to engage said gears and to restore said gears to a normal position, a sleeve rotatable on each shaft, a resilient clutch to connect each sleeve to its associated dial, a second mutilated gear on each sleeve, a second horizontal resetting rack means slidable to engage said second mutilated gears and to restore said second mutilated gears to a normal position, means to enable selective operation of said two resetting racks, and means to enable selective differential adjustment of each of said dials relative to its associated sleeve.

JOHN L. MOODY.
